UNITED STATES PATENT OFFICE.

PHILIPP MOELLENDICK, OF NEW YORK, N. Y.

GAS-BURNER ATTACHMENT.

1,414,146.

Specification of Letters Patent. Patented Apr. 25, 1922.

Application filed July 21, 1921. Serial No. 486,405.

To all whom it may concern:

Be it known that I, PHILIPP MOELLENDICK, a citizen of the Republic of Germany, residing in the borough of Manhattan, city, 5 county, and State of New York, have invented an Improvement in Gas-Burner Attachments, of which the following is a specification.

This invention relates to a gas burner attachment designed to concentrate the flame from a gas burner and to retain the heat within the same by preventing the influence of air currents from dissipating the heat to places other than that to which it is desired 10 to direct the same. I am aware that heretofore various forms of gas burner and gas stove attachments have been made for similar purposes. For example, as shown in Letters Patent No. 1,142,603, granted to me 15 June 8, 1915, there is shown and described a gas stove attachment for accomplishing similar purposes. In the form of the invention shown in the aforesaid patent, however, the structure is adapted more or less exclusively 20 to be employed in the manufacture of new gas ranges and is not adapted, readily, to be applied to gas ranges which are designed in their manufacture to be made without the same. The object of my present invention, 25 consequently, is to provide a relatively inexpensive article which may be handled, for example, in a mail order business and may be readily applied to a gas burner of substantially any type to accomplish the desired 30 objects in a sufficiently practical way to effect a material saving in the use of gas.

In carrying out my invention the attachment preferably comprises a plurality of sections made of sheet metal or other similar 40 material adapted normally to lie flat so as to be readily packed for shipping and to be assembled by attaching the sections to one another which when thus connected may be secured to the gas burner by means provided 45 for this purpose so as to surround the gas burner and to direct the flame from the same and at the same time form a chamber for retaining the heat and directing the same for proper application.

50 In the drawing:

Fig. 1 is a central section illustrating one form of gas burner with my improved attachment secured thereto.

Fig. 2 is an inverted plan of the same.

55 Fig. 3 is a plan on a scale larger than that

shown in Figs. 1 and 2 of one section of my improved attachment.

Fig. 4 is a similar view of another section of the attachment, and

Fig. 5 is an elevation illustrating the manner in which the attachments are adjustably connected.

Referring to the drawing, it will be seen that in carrying out this invention the same is applied to a gas burner. The gas burner 60 may be of any type whatsoever. As illustrated, I have shown a circular form of burner indicated at 10 which, as is customary, is connected to a supply pipe 11 by which it may also be supported. The burner 65 includes the circular or ring member 12 in the upper portion of which there are the customary holes or apertures 13 through which the gas passes and at the orifices of which the gas burns.

The attachment made in accordance with this invention preferably comprises strips of sheet metal or other similar material which is indicated in Figs. 3 and 4 preferably made on arcs of circles so as to be assembled to 70 form a conical attachment. One section of the attachment is indicated at 14, another section at 15. In the lower edges both of these sections may be provided with notches 75 16 to receive the arms of a gas burner when the radial arm form of burner is employed. Also as illustrated one of the members as indicated at 15 is provided at or adjacent its extremities with fingers 17 and 18 adapted to be turned over to the positions shown in 80 Fig. 4 so as to receive the ends of the section 14 as indicated in Fig. 5 whereby as will be understood the sections of the attachment are assembled and adjusted to the necessary diameter for use on any particular 85 burner. The section 14 is furthermore provided with a projection 19 and the section 15 with a similar projection 20 which, when the parts are in their assembled positions, are oppositely disposed so as to be turned in 90 against the outer surface of the burner irrespective of the type of the same in order to 95 secure the attachment in position.

It will be understood that while I have 100 herein shown and described a gas burner attachment comprising two sections that any 105 desired number of sections may be employed, and furthermore that while I have shown and described overturned fingers on one section for engaging the adjacent end of an 110

other section for securing the sections adjustably to one another, and have shown projections adapted to be inturned to secure the attachment in place on a gas burner, 5 other similar and equivalent means may be employed without departing from the nature and spirit of my invention.

I claim as my invention:

1. A gas burner attachment comprising a plurality of sections, each section being made from sheet metal cut in the form of an arc of a circle, means for attaching the sections adjustably to one another, and means for securing the attachment to a gas burner, the 10 said sections when thus assembled and connected assuming a conical formation to direct the heat toward the center of the burner.
2. A gas burner attachment comprising a plurality of sections, each section being made 15 from flat sheet metal in the form of an arc of a circle, overturned fingers adjacent the ends

of one section adapted to receive the end of the next adjacent section for adjustably connecting the sections to one another so that when connected the sections assume a conical 25 configuration, and means for securing the attachment in position to a gas burner.

3. A gas burner attachment comprising a plurality of sections, each section being made from flat sheet metal in the form of an 30 arc of a circle, overturned fingers adjacent the ends of one section adapted to receive the end of the next adjacent section for adjustably connecting the sections to one another so that when connected the sections assume a 35 conical configuration, and an extension from the lower edge of each section adapted to be inturned to engage the surface of the gas burner to secure the attachment in position thereon.

Signed by me this 12th day of July, 1921.
PHILIPP MOELLENDICK.
